United States Patent Office

Des. 215,828
Patented Nov. 4, 1969

215,828

BUILDING

Thomas H. Boulay, 6600 Blackfoot Pass,
Edina, Minn. 55435

Filed Sept. 13, 1968, Ser. No. 13,534

Term of patent 14 years

Int. Cl. D25—04

U.S. Cl. D13—1

Fig. 1

Fig. 2

Fig. 3

FIG. 1 is a front view of the building showing the embodiment of my new design;

FIG. 2 is a side view of the building;

FIG. 3 is a rear view of the building;

The side of the building not shown is a mirror image of FIG. 2.

I claim:

An ornamental design for a building, as shown and described.
